UNITED STATES PATENT OFFICE.

WILLIAM D. REDRUP, OF HUNTINGTON, INDIANA, ASSIGNOR TO THE MAJESTIC COMPANY, OF HUNTINGTON, INDIANA, A CORPORATION OF INDIANA.

WINDOW.

Application filed March 29, 1926. Serial No. 98,172.

This invention relates to window-pane holding means, and particularly to such a means adapted for use in connection with metal coal chute windows.

5 The object of my invention is the provision of means of the character described, which is simple and inexpensive in its construction, is adapted to permit an easy and rapid replacement of window panes when 10 they become broken, and is compact in form.

The invention is fully described in the following specification, and while it is capable of embodiment in numerous forms, a 15 preferred embodiment thereof is illustrated in the accompanying drawings, in which,—

Figure 1 is an outer side view of a coal chute window embodying the invention. Fig. 2 is a cross-section thereof on the line 20 2—2 in Fig. 1. Figs. 3 and 4 are enlarged sectional views on the line 3—3 and 4—4, respectively, in Fig. 1, and Fig. 5 is a fragmentary inner side view of the window member.

25 Referring to the drawings, 1 designates a window casing or frame, in the present instance, comprising a metal casting and adapted to be secured marginally to the opening of a basement window or the like 30 to which it is to be fitted.

A window or closure member 2 is hinged to the frame 1 and adapted to seat at its edge against the inner marginal edge portion of the frame. This member is preferably stamped from sheet metal, and, in the 35 present instance, has three openings 3 closed by removable or replaceable panes 4 of glass or other suitable material.

In carrying out the invention, a channel 40 5 is provided in the inner side of the closure member 2 marginally entirely around the space formed by the openings 3 and a channel 7 is also provided lengthwise in the inner side of each cross-bar 6, which 45 divide the closure member into the openings 3.

The free edge wall of the channel 5 and both edge walls of the cross-bar channels 7 are preferably turned outwardly with relation to the respective channels to form seats 8 at the inner side of the member 2 against which the respective adjacent marginal edge portions of the panes 4 seat. The plane of the seats 8 is preferably out-

wardly offset a slight distance from the 55 inner surface plane of the closure member, so that the leg or side wall of the marginal channel 5 which is disposed away from the openings 3, is longer than the other leg or 60 side wall of the channel.

The panes 4 are mounted within a rectangular frame 9 of angle-iron form in cross-section, with the outer laterally projecting or pane confining flange thereof of greater transverse length than the thickness of the pane, so that the free end of such leg is adapted to project beyond the inner sides of the adjacent edges of the panes and into the channel 5 in engagement with the outer wall of such channel, as indicated. This permits lateral movement of the frame when properly seated against the closure member 2. The other flange of the frame 9 projects inwardly relative to the frame and bears against the respective 75 panes 4 in opposition to the seats 8 formed by the outwardly turned edge wall of the channel 5.

The adjacent edges of the several panes 4 are spaced in opposition to the cross-bars 6 by filler strips 10 of channel form and preferably of sheet metal. The outer end edges of the leg portions of the channel strips 10 are turned outwardly over the adjacent marginal edge portions of the 80 respective panes 4 and in opposition to the seats 8 of the cross-bars 6.

The frame 9 with the window-panes 4 and spacing strips 10 mounted therein is held seated against the inner side of the 85 closure member 2 with the window panes 4 bearing against the seats 8 by angled clamping fingers 11 which engage over the edges of the frame 9 at spaced distances therearound, and are held to the closure 90 member 2 by bolts 12.

An important function of the channels 5 and 7 is to provide recesses for receiving putty or other suitable sealing compound when it is desired to prevent the passage of 100 wind and rain through the window around the edges of the panes.

It is evident that I have provided a compact, rigid, durable and inexpensive window pane securing means for use in connection particularly with metal closure members, which means is composed of few parts, holds the window-panes securely to 105

the closure member, and permits of an easy and rapid replacement of the panes when breakage occurs.

I wish it understood that my invention is not limited to any specific construction, arrangement or form of the parts, as it is capable of embodiment in numerous forms without departing from the spirit of the claims.

Having thus described my invention, what I claim as new and desire to secure by Letters Patent is:

1. A closure member having an opening therein and a marginal channel around the opening with the edge wall of the free leg of the channel forming a seat for a window pane, a window pane holding frame of angle iron form in cross-section having one flange projecting edgewise into the channel and its other flange adapted to grip a pane in opposition to the free edge wall of the channel, said channel being of a width so as to permit the first named flange of the angle iron frame to be adjusted laterally of the channel, and means for detachably securing the frame to the closure member.

2. A closure member having a plurality of window openings therein and having integral cross-bars separating the openings from each other, said member having its inner side formed marginally around said openings with a channel and having the inner sides of its cross-bars channelled, a window pane for each opening seating against the free edge wall of the marginal channel and the adjacent free edge wall of the cross-bar channel, a frame of angle iron form in cross-section having an inwardly turned flange opposing the seating of the panes against the free edge walls of the chan-

nels and having its other flange projecting edgewise into the marginal channel and adapted to coact with the outer wall of such channel to prevent sidewise movements of the frame relative to the closure member, means for releasably securing the frame to the closure member, and channeled spacing strips interposed between the adjacent edges of the panes with their looped portions adjacent the channels of the cross-bars and their free edge portions turned outwardly over the adjacent edges of the panes.

3. In a closure member, a body having an opening therein and a marginal channel around the opening, the hollow interior of which channel faces rearwardly of the body, the free leg of the channel forming a window pane seat, a window pane holding angle iron frame having one flange projecting edgewise into the interior of the channel, and means to secure the frame in position, the channel being of a size to permit lateral movement of the flange in the channel, and to receive a sealing agent.

4. In a closure member, a body having an opening therein and a hollow cross-bar extending across the opening, a pair of window panes in the opening having spaced adjacent edges with the space between the edges in register with the interior of the hollow cross bar, and a filler member engaged with the inner faces of the panes and with said edges thereof and having a part spaced from the interior of the cross bar, so as to receive a sealing agent in and between the interior of the cross bar and the filler member.

In testimony whereof I have hereunto signed my name to this specification.

WILLIAM D. REDRUP.
